UNITED STATES PATENT OFFICE.

ELAINE MARTIN DREW, OF BARRE, VERMONT.

CRIB COVER.

Application filed April 21, 1923. Serial No. 555,892.

To all whom it may concern:

Be it known that I, ELAINE M. DREW, a citizen of the United States, and a resident of Barre, in the county of Washington and State of Vermont, have invented a new and Improved Crib Cover, of which the following is a full, clear, and exact description.

The present invention relates to new and useful improvements in children's crib covers.

It is one of the primary objects of the invention to secure the covers for children's cribs in such a manner that the covers will not be displaced relative to the crib and the occupant thereof upon restless movements of the occupant.

It is another object of the invention to so construct crib covers that the occupant of the crib is free to turn upon one or the other side without disarranging the covers.

It is a further object of the invention to so construct the crib covers that the occupant of the crib may be removed and replaced in the crib without disturbing the covers.

It is a still further object of the invention to so construct a crib cover that the occupant of the crib will be relieved of the weight thereof.

With the above and other objects in view, reference is had to the accompanying drawings, in which—

Figure 1 is a plan view of a child's crib showing the manner in which the covers are used in connection therewith;

Fig. 2 is a detail plan view of one portion of the covers;

Fig. 3 is a similar view of another portion of the covers;

Fig. 4 is a transverse sectional view of the crib showing the manner of supporting the covers out of contact with the occupant of the crib.

Referring more particularly to the drawings, the reference character 5 designates the crib, and said crib is provided with a mattress 6 in any well-known manner.

The cover comprises two sections 7 and 8 of any suitable material, such, for example, as a blanket. Secured to the section 7 of the blanket or other heavy cover is a lining sheet 9 of cotton or linen, and secured to the section 8 is a similar lining 10, it being understood that said linings or sheet portions are carried upon the interior of the blanket or heavy covering.

As more clearly shown in Fig. 2, the section 8 of the heavy cover is provided with a cut-out portion 11, and the lining 10 of said portion 8 is folded outwardly through 60 said neck opening or cut-out portion 11 to provide a collar 12 therefor. This section 8 is provided with a plurality of buttonholes or other suitable fastening elements, 13.

The section 7 of the heavy cover is likewise provided with a slightly cut-out portion 15 forming one side of the neck portion 11. Defining this cut-out portion 15 of the section 7 and overlapping said section 7 is a semi-circular flap 16, it being 70 understood that this flap 16 is formed of the same material as the sheet or lining 9 of the section 7, and is secured thereto either by sewing or in any suitable manner. The section 7 is provided with a plurality of 75 buttons 17 and said buttons 17 are adapted to be engaged by the buttonholes of the section 8 to retain the cover in position.

The device functions in the following manner: One side of the device is opened 80 by disengaging the buttons 17 from their respective buttonholes 13, and the section 7 together with its sheet section or lining 9 is turned back and the child is placed within the crib. After this has been done, 85 the open side is closed by engaging the buttons 17 with their respective buttonholes 13, and with the neck opening 11 receiving the neck of the child.

It is to be understood, of course, that the 90 sides of the sections 7 and 8 are folded beneath the mattress, as clearly shown in Fig. 4.

When it is desired to remove the child from the crib, it is only necessary to undo 95 one side of the cover, which action permits of a ready removal of the child.

It is obvious that any number of heavy cover sections may be employed by simply laying them over the cover sections 7 and 100 8 already in use.

The reference character 25 designates safety pins or the like, and extending through said safety pins is a cord 26. The ends of this cord 26 are secured by tying 105 27, as indicated by the reference character 27, to the head and foot sections of the crib.

By the above described construction it is apparent that the cover section 7 may be supported out of contact with the occupant 110 of the crib, thus relieving said occupant of the weight of the covers.

22

By bringing the sheet or lining sections outwardly of the heavy cover sections 7 and 8, at the neck opening, it is apparent that the heavy cover sections are protected from being soiled by contact with the body of the occupant of the crib.

While in the present instance the means for fastening the sections 7 and 8 together has been described as being buttons and buttonholes, it is obvious that other types of fasteners, such as snap fasteners, tapes, or the like, may be employed for this purpose, and the invention is not limited, therefore, to the specific form of fastener shown.

15. From the foregoing it is apparent that the present invention provides a new and improved form of cover for children's cribs in which the occupant of the crib is free to move without disturbing the cover, thus assuring that the occupant will at all times

have the protection thereof. Furthermore, the invention provides for the ready removal and replacement of the occupant relative to the crib without a disturbance of the covers, and by means of the cord 26, 25 the cover is maintained out of contact with the occupant of the crib.

What is claimed is:

A cover for cribs comprising two sections, each of which is provided with a 30 cut-out portion serving to form a neck opening when the sections are placed together, means for securing the sections together to form a single cover, and a lining of lighter material for each of said sections, said linings extending to the outer face of the cover sections and so formed as to overlie the defining edge of the neck opening therein.

ELAINE MARTIN DREW.
